ISAAC PEYTON
INVENTOR

BY Fred D. Silboway

ATTORNEY

UNITED STATES PATENT OFFICE.

ISAAC PEYTON, OF SPRINGFIELD, ILLINOIS.

NUT-LOCK.

1,106,316.

Specification of Letters Patent.

Patented Aug. 4, 1914.

Application filed July 25, 1913. Serial No. 781,268.

To all whom it may concern:

Be it known that I, ISAAC PEYTON, a citizen of the United States, residing at Springfield, in the county of Sangamon and State 5 of Illinois, have invented new and useful Improvements in Nut-Locks, of which the following is a specification.

My invention relates to improvements in nut locks for rail joints.

10 An object of my invention is to provide a device which will afford means for preventing the loosening of the nuts on the bolts provided for the purpose of uniting the joining members to the meeting ends of 15 a pair of rails.

Another object is to provide a device of the above character which will be efficient and simple in design, and which may be easily and quickly applied to its working 20 position.

With the above and other objects in view, my invention consists of certain peculiarities of construction and arrangement of parts which will be hereinafter described 25 and pointed out in the appended claims.

In the drawings:—Figure 1 is a perspective view of the device of my invention, shown in its working position at the rail joint. Fig. 2 is a sectional view through the 30 nut locking device. Fig. 3 is a plan view of the vertical nut lock plate. Fig. 4 is a front elevation of the horizontal nut locking plate.

Referring now to the drawings, numeral 35 1 designates the meeting ends of two rails, forming the rail joint A, in the usual well known manner, reinforcing member 5 overlapping the joint and positioned on the outer side of the rail. Reinforcing member 40 5 is provided with projecting feet 7, at right angles to the up-standing reinforcing portion, and adapted to be engaged by spikes 9 in fixed relation to railway ties 2. Bolts 10 are adapted to pass through reinforcing member 5 and rails 1, having heads 45 on the inner side of the rails, and nuts designated as 10' against the outer face of reinforcing member 5.

In the angle formed by reinforcing mem-

ber 5 and the projecting feet 7, a nut locking device is provided, consisting of a horizontal plate 12 and a vertical plate 13. Said plates are hinged together by means of lugs 14 carried on the lower face of plate 13, said lugs being adapted to mesh with cut-out 55 portions 15 carried by plate 12. Pins 16, or similar suitable means, are provided for hinging the two members together. Slots 19 carried in the upper portion of vertical lock plate 13, and slots 20 in horizontal 60 lock plate 12 are adapted to mesh with nuts 10' and 11' respectively, said slots being of sufficient width to allow the nuts to fit loosely therein. It will be readily seen that the nut locking device, when fitted in place 65 in the angle provided on reinforcing member 5, will prevent the nuts from further turning on their bolts. Springs 17 are rigidly attached to the vertical lock plate 13 by rivets 18, or similar means, said 70 springs having free ends adapted to press downward against the horizontal plate, for the purpose of holding the plates in a stationary position after their application about the nuts.

From the foregoing description it will be clearly understood that the device of my invention provides an improvement in nut locks, which will effectively provide means for locking the nuts at a rail joint.

It will also be seen that my device is simple in design, and that it may be easily and quickly applied to its working position.

Changes within the spirit and scope of the appended claims may be made as it is 85 obvious that the details of construction and arrangement of parts may be varied in many ways.

Having thus described my invention, what I claim is:—

1. In a device of the character described, the combination with bolts and nuts uniting rail ends with a supporting plate and a reinforcing member, of a nut locking device having a horizontal lock plate hinged to a vertical lock plate, said lock plates provided with slots adapted to keep said nuts from turning upon said bolts, and springs carried by one

of said lock plates and adapted to hold the | said lock plates in working position, sub-
stantially as described.

2. In a device of the character described, | the combination with bolts and nuts uniting
the rail ends with a supporting plate and a re-
inforcing member, of a vertical nut locking
plate, a horizontal nut locking plate, said |

nut locking plates provided with slots keep-
ing said nuts from turning upon said bolts, 10
and spring means for holding said locking
plates in position, substantially as described.

ISAAC PEYTON.
